STEAM-APPLYING DEVICE

Application filed December 17, 1938. Serial No. 326,692.

Our invention relates to improvements in steam-applying devices, and it consists of the combinations, constructions and arrangements hereinafter described and claimed.

An object of our invention is to provide a device for applying superheated dry steam to the surface of dress materials and the like for improving the texture and general appearance of the same, as for instance, for raising the nap of velvet and similar materials, for removing wrinkles from various materials, restoring the crinkle in chiffon material, for glazing furs, treating beaded dresses and other purposes.

More specifically, we propose to arrange a heating element in an inclosed container of water, conveying the steam that is formed therefrom to a superheating coil, and subsequently discharging the dry steam onto the surface of the texture.

A further object of our invention resides in providing a device of the type described which is simple in construction, durable and efficient for the purpose intended.

The long-established method of pressing fabrics consists primarily of dampening the surface of the fabric with water in any suitable manner and later passing a pressing iron thereover. Continual application of such a method will ultimately result in flattening the nap, which normally produces an undesirable glossy appearance.

In order to overcome this objectionable feature of pressing, we propose to hang the textures in a substantially vertical position, and then pass our device over the surface thereof, which will materially aid in renewing the texture.

Our invention is illustrated in the accompanying drawing, forming a part of this application, in which

Figure 1 is a longitudinal section of our device;

Figure 2 is a top plan view of Figure 1; Figure 3 is a vertical end elevation of the device; and

Figure 4 is a transverse section taken on line 4-4 of Figure 1.

While we have shown only the preferred form of our invention, we wish it to be un-

derstood that various changes or modifications may be made within the scope of the appended claims without departing from the spirit of the invention.

In carrying out our invention, we provide an iron A that is divided interiorly into a water-reservoir compartment B, and a steam-retaining compartment C, the two compartments being interconnected by means of a coil D, which is so arranged as to encircle a heating element E.

Referring now to Figure 1, it will be noted that a cylindrical housing 1 extends along the longitudinal axis of the compartment B, and is held in spaced relation with the side walls 2 of the container by spiders 3 and 4. One end of the housing is threaded into a wall 5 as at 6, the opposite end thereof being supported by a wall 7. A packing gland 7' prevents the liquid in the reservoir from leaking between the wall 7 and the housing 1. The housing opens into the compartment C and may be considered as a section of the same extending into compartment B.

In order that the water in the container B may be changed to steam, we have disposed a heating element interiorly of the housing 1, and preferably extending the entire length thereof. It is apparent that this particular construction will present a relatively large heating surface, and will, therefore, develop the maximum efficiency for the heat units consumed.

For the purpose of heating the element E, we have operatively connected the element to contact terminals 8, which are adapted to be received in corresponding recesses that are formed in a standard electric plug, not shown.

It is thus apparent that as long as the heating element continues to function, steam will be produced from the water surrounding the housing, the steam in turn entering the forward portion B' of compartment B by way of an aperture 9.

We now have the steam in the forward portion of compartment B, but it contains a relatively high percentage of moisture which would be injurious to fabric if contacted therewith in this form. We have readily overcome this objection by conveying the

steam through the coupling 10, and on into the coil D that is arranged in concentric relation with the heating element E. Through this medium, the steam is superheated before it is discharged from the end 11 of the coil into the compartment C.

As a means of caution, we have placed a safety valve 12 in the upper wall of the compartment B' through which an excess amount of steam may escape should the developed pressure be relatively high. While this valve may be of any suitable construction, we prefer to use that type of valve in which a ball 13 is urged into contact with the valve seat 14 by a spring 15.

Figure 2 discloses the shape of the forward portion of the iron as having two oppositely disposed walls 16 and 17 that gradually converge into a common point 18.

The bottom 19 of the compartment C is inclined upwardly at a slight angle with respect to a horizontal plane which passes through the longitudinal axis of the heating element. A fabric member 20 is secured around the bottom 19 by means of a cord 21, the fabric entirely surrounding the opening 22 that is formed in the bottom 19 of the iron. This fabric serves to disperse the steam evenly over the texture with which it contacts.

A handle 23 is secured to the iron by bolts 24 which extend into threaded recesses 25. The iron may be readily and conveniently moved from place to place by the handle in the customary manner.

The compartment B may be filled from time to time through a passageway 26 that is normally closed by a removable cap 27, see Figures 2 and 3.

From the foregoing description of the various parts of the device, the operation thereof may be readily understood. Assuming that the reservoir is properly filled with water, the heating element E is then rendered active by connecting the terminals 8 to a source of current. When in use the device is held in a substantially upright position and the steam that accumulates above the surface of the water rises into the forward section B' of the compartment B, then passes through the super-heating coil D and is finally discharged into the compartment C. The steam is then forced through the fabric 20, and may thus contact with any texture that is arranged in close proximity with the bottom 19 of the iron.

It should be noted that our device may not only be used for the treatment of dress materials but will be found advantageous in the treatment of furniture, millinery, drapes and other materials. The steam is applied while the material is suspended and in many cases it will be found feasible to apply the steam while the dress is being worn.

We claim:

1. A steam applying iron having a large discharge opening and a cloth stretched thereacross, means for admitting liquid into the iron, means within the iron for changing the water into steam and means within the iron for superheating the steam and means associated therewith for discharging the super-heated steam through the cloth.

2. A steam applying iron comprising a substantially cylindrical rear portion and a widened front portion with a slanting bottom formed with a large discharge opening and a cloth stretched across the opening, a partition running substantially parallel to the slanting bottom and having a hub disposed axially of the cylindrical portion, a tube extending through the rear end of the iron and threaded into the hub and communicating with the front compartment, the tube being spaced from the cylindrical portion so as to be entirely surrounded thereby, a heating unit extending through the tube and a super-heating coil surrounding the heating unit and having its receiving end communicating with the front end of the rear compartment and its discharge end with the front compartment.

3. A steam applying iron having a water compartment and a steam compartment, with a section of the latter compartment projecting into the former, a heating unit in said section for converting the water into steam, a coil surrounding the heating unit and interconnecting the two compartments so as to allow steam to pass therethrough from the water compartment to the steam compartment and to be superheated therein, and means for discharging the superheated steam from the latter compartment.

4. A steam applying iron having a water compartment and a steam compartment, with a section of the latter compartment projecting centrally into the former so as to be surrounded by water on all sides, a heating unit in said section for converting the water into steam, a coil surrounding the heating unit and interconnecting the two compartments so as to allow steam to pass therethrough from the water compartment to the steam compartment and to be superheated therein, and means for discharging the superheated steam from the latter compartment.

5. A steam applying iron having a cylindrical water compartment and a steam compartment forming a longitudinal extension thereof, a tube extending axially through the water compartment and opening into the steam compartment, a heating unit in said tube for converting the water into steam, a coil surrounding the heating unit and interconnecting the two compartments so as to allow steam to pass therethrough from the water compartment to the steam compartment and to be superheated therein, and means for discharging the superheated steam from the latter compartment.

6. A steam applying device comprising a body portion, said body portion being divided interiorly into two compartments, one of said compartments having means for admitting a liquid thereinto, and a heating element for changing the liquid to steam, the other compartment being formed with an opening in the side wall thereof, a fabric disposed over said opening and a coil connecting the two compartments, the coil being arranged in heat exchange relation to the heating element for superheating the steam.
